LOOM

Application filed February 1, 1928. Serial No. 251,151.

This invention relates to looms and particularly to mechanism to be applied to a plain loom for controlling the pattern as it is woven into the cloth to form checks such as occur in handkerchief cloth, dimity and the like, or broken stripes such as are formed in shirting, dress goods and the like.

As is well known in the art, plain looms, i. e. looms employing two harnesses or the equivalent thereof for producing plain weave, are idle for certain periods of time due to the fact that an order for fancy goods must be run off. Heretofore fancy goods, i. e. cloth having a pattern woven therein has been made on a loom especially adapted for that purpose. Such a loom employs several harnesses usually eight to twenty of special make and a complicated harness controlling mechanism and is generally used for no other purpose than to weave fancy goods.

Pattern controlling mechanisms now commonly employed in the textile industry are complicated and therefore relatively expensive and require considerable time in setting up and making ready for the weavers. Furthermore, they require considerable power for operation due to their many parts and complicated construction and their speed is limited with a consequent limited output. They also require considerable attention on the part of the loom fixer and weaver who in turn are limited as to the number they can take care of, with a consequent high cost in overhead expense. Furthermore the drawing in operation for these mechanisms which consists of drawing each individual end from the warp supply through the eyes of the harness heddle and reed, must be done by hand, which operation requires considerable time and labor and keeps the overhead cost high.

One object of the present invention is to provide simple and relatively inexpensive pattern controlling mechanism for application to a plain loom so that pattern cloth can be woven thereon or the loom may be used for weaving plain cloth.

Another object is to provide mechanism that can be easily and quickly applied to such a loom and taken care of after its application with a minimum amount of labor.

Another object is to provide mechanism requiring little extra power to operate and capable of a relatively higher speed.

A further object is to provide mechanism which will require little attention from the loom fixer after it is set up and in operation.

A still further object is to provide mechanism which will permit the drawing-in operation to be done by the warp drawing-in machine.

These and other objects of the invention will be clearly understood from the following description in conjunction with the accompanying drawings, in which;

Fig. 1 is a side elevation of a loom having attached thereto pattern controlling mechanism embodying the invention, the parts being shown in operative position.

Fig. 2 is an enlarged vertical section taken on the line 2—2 of Fig. 1.

Fig. 3 is a view in perspective of the mechanism shown in Fig. 2.

Figs. 4 and 5 are sectional views taken on the lines 4—4 and 5—5 respectively of Fig. 1.

Fig. 6 is a sectional view taken on the line 6—6, Fig. 3, the parts being shown in inoperative position.

Fig. 7 is a diagram of "wide check weave" such as handkerchief cloth produced by a loom equipped with mechanism embodying the invention.

Fig. 8 is a similar view of "narrow check weave" such as dimity.

Fig. 9 is a detail view of the pattern chain employed in producing the weave shown in Fig. 8.

Fig. 10 is a diagram of "broken stripe weave" shown as dress goods.

Fig. 11 is a detail view of the pattern chain employed in producing the weave shown in Fig. 10.

As herein shown the pattern controlling mechanism embodying the invention is applied to a plain loom of the two harness type. Referring to Fig. 1 of the drawings, at F 95 is shown one of the side frames of such a loom which is provided with bearings for the crank shaft 20, the cam shaft 21, the shaft 22 of spool W from which the warp threads *w* are drawn in the process of weaving; and 100

the shaft 23 of the cloth drum R upon which the finished cloth C is wound after passing over the breast beam B. The crank shaft 20 has fixed thereto a pulley 24 by which it is driven from any suitable source of power (not shown). It is provided with cranks 25 which impart an oscillating motion to the lay beam l carried by the lay swords 26 to which the cranks are connected by intermediate links 27. The lay swords are pivoted at 301 to the frame of the loom. The cam shaft 21 is driven by the crank shaft 20 which has driving connection therewith by gears 8.

The takeup motion of the loom, shown at 15 T, is of the intermittent type and comprises a train of gears g and a ratchet 28 which receives motion from a pawl 29 carried by an arm 30 pivoted at 31 to the frame and actuated by one of the lay swords 26. The ratchet 28 is locked against retrograde movement after each action of the pawl 29 by one arm 32 of a lever 33 pivoted at 31 to the frame, said arm acting as a locking pawl. This motion draws down the cloth after it 25 is woven and winds it upon the drum R.

The shedding motion of the loom is indicated at M and includes shedding cams, one treadle, front and back harnesses, a coiled spring and a harness roller. The shedding cams indicated at c and c' are mounted fast on the cam shaft 21. The cam c operates the treadle t which is pivoted at 34 to the frame. The front and back harnesses are indicated at h and h' respectively and are connected 30 at their upper ends to the harness roller n. At its lower end the front harness h is connected to the treadle t. The treadle ordinarily supplied for the rear harness h' has been removed and the rear harness has been connected to the floor by a coiled spring 35. As 35 the front harness h is depressed by the extended portion of its cam c, the rear harness h' is raised thus storing up energy in the spring 35. When the front harness h is 40 permitted to rise the rear harness h' is depressed under the action of the spring 35. In this manner the shed indicated at S is formed which permits the passage therethrough of the shuttle s to lay the weft threads 45 or filling. The shuttle s, actuated by the picking motion (not shown), travels on the lay beam l which is actuated by the crank shaft as heretofore described. At r is shown the reed which beats up the last pick of the 50 filling after it has been laid in the shed by the shuttle, the constant repetition of which results in the formation of the cloth.

With the exception of the omission of one 55 treadle and the addition of the spring 35 which connects the rear harness h' to the floor, the foregoing mechanism may be of any well known construction as it forms no part of the present invention except in its combination therewith to bring about the desired 60 results.

Referring now to Fig. 7 of the drawings there is shown in diagram a fragmentary view of handkerchief cloth as it comes off the loom wherein a designates the body portion which is of plain weave, b designates one 70 of the borders made by the weft threads or filling and which in this instance comprises a group of eight cords shown at 36 and seven single threads or picks shown at 37. Each cord of this border is made up of three threads 75 or picks and each pair of cords has one of the single threads or picks therebetween. At d is shown one of the hems which is of plain weave and at e one of the so-called "severing cords" which in this instance is 80 made up of three threads or picks. As is well known to those skilled in the art handkerchief cloth is made up in a large bolt comprising a large number of handkerchiefs and the severing cords are woven into the cloth 85 at predetermined intervals to define the individual handkerchiefs, it being only necessary for the handkerchief maker to cut along these lines to divide the cloth into individual handkerchiefs which may afterwards be finished up in any well known manner. At f is shown one of the borders made by the warp threads which is similar in construction to the border previously described.

It is with the weaving of the borders b 90 and the severing cords e made of the weft threads or filling that the invention is concerned and it is one of the objects of the present invention to provide pattern controlling mechanism adapted for application to a 100 plain loom of the two harness type and capable of producing the pattern above referred to.

In accordance with the present invention and with particular reference to Figs. 1 to 3 105 inclusive of the drawings, at 40 is indicated a shaft journaled in bearings 41 secured to a cross member 2 connecting the side frames F of the loom. A portion of this shaft extends outwardly beyond one of the side frames 110 and has secured thereto by a set screw 42 a sprocket 43 which engages a chain 44 herein termed the "pattern chain". This chain is provided with a series of cams for a purpose to be hereinafter described, and extends upwardly in a plane parallel to the loom frame, and at its upper end runs over a sprocket 45 loosely mounted on a stud 46 which is adjustably secured to a bracket 47 located between said chain and the side frame of the 115 loom. The bracket 47 is provided with an elongated slot 48 for the reception of the threaded end portion 49 of the stud 46, said stud being fixed in adjusted position by a nut 50. The bracket is itself adjustably secured 120 to the side frame of the loom by a stud 51 the reduced threaded portion 52 of which is received in an elongated slot 53 in the side frame F to which the inner end of the stud 54 is clamped by a nut 54. The stud 51 is pro- 130

vided at its outer end with a reduced threaded portion 55 which is received in the slot of the bracket to which it is clamped by a nut 56. The bracket terminates at its lower end in a fork indicated at 57 which engages the shaft 40 and is held immovably in place thereon between collars 58.

It will thus be seen that adjustment is provided between the side frame Y of the loom and the bracket 47 for the pattern chain, and furthermore between the bracket 47 and the stud 46 which carries the upper sprocket 45. In this manner various lengths of pattern chains for a wide variety of patterns may be employed.

The pattern chain 44 comprises a series of links for engagement with the sprockets 43 and 45 and is provided on its periphery with knobs or cams arranged in groups and adapted, at certain periods of time during the operation of the loom, to actuate mechanism to engage the treadle *t* and restrain the harnesses. As shown in Figs. 1 and 3 this mechanism includes an arm 60 having its upper end loosely mounted on a stud 61 adjustably secured to an extension 62 on the bracket 47. The lower end of the arm 60 has attached thereto a wire 63 that is connected to a belt 64 that passes around pulleys 65 and is connected to a wire 66 that is attached to the lower end of a latch 3 pivoted intermediate its ends at 4 to a post 68. The post 68 is adjustably secured by bolts 67 to a slotted standard 69 fixed to the floor directly under the forward end of the treadle *t*. The upper end of the latch 3 is provided with a hook 5 adapted to engage a pin 6 on the forward end of the treadle when the treadle engaging mechanism is actuated. The hooked end of the latch 3 is released to free the treadle, when the treadle engaging mechanism is inoperative, by a coiled spring 7 attached at one end to the post and at the other end to the wire 66 as shown in Fig. 1. The arm 60 is provided, intermediate its pivot point 61 and its connection with the flexible member which connects it to the latch 3, with a roller 9 which lies in the path of movement of the cams on the pattern chain and normally rests against the plain links thereof due to the force exerted by the spring 7 in retracting the connections 63, 64 and 66.

The cams on the pattern chain are as heretofore stated arranged in groups, and as shown for the particular pattern illustrated in Fig. 7, comprise a group of eight cams indicated at 70, a single cam 71, and another group of eight cams indicated at 72. Between each pair of cams in the eight-cam groups is a single plain link. Between the group 70 and the single cam 71 are three plain links indicated at 73, and between the single cam 71 and the next group 72 are five plain links indicated at 74 and between each group

of cams to complete the chain are six plain links indicated at 75.

The group of eight cams indicated at 70 actuates the treadle engaging mechanism above described to restrain the harnesses while the eight cords 36 of the border *b* shown in Fig. 7 are being laid. The seven plain links in this group permit the treadle engaging mechanism to release the harnesses under the action of the spring 7 at which time the seven single picks in the border *b* are being laid. As shown in Figs. 1 and 3 the first cam of the group 70 is engaging the roller 9 of the arm 60. This action has swung the arm 60 on its pivot to the left as viewed in Fig. 1, causing the arm to exert a pull on the lower end of the latch 3 through the intermediate connections 63, 64 and 66 and force the hooked end 5 of said latch into engagement with the pin 6 on the forward end of the treadle. At this time the harnesses are held in a fixed position thus keeping the shed S in the position shown in Fig. 1 while the three picks constituting the first cord of the border *b* are being laid. The single cam 71 actuates the treadle engaging mechanism in like manner to restrain the harnesses while the severing cord *e* of three picks is being laid. The next group of eight cams indicated at 72 actuates the treadle engaging mechanism to restrain the harnesses while the next border (not shown) which is similar to border *b* is being laid.

The pattern chain 44 is moved to actuate the treadle engaging mechanism by means which will now be described. Secured to the cam shaft 21 for rotation therewith is an eccentric 76 which actuates a pawl 77 having a hook-shaped end *k* and adjustably secured by a set screw 78 to a projection 79 on the eccentric strap 80. The pawl 77 overlies a ratchet 81 secured by a set screw 82 to the shaft 40 and is adapted at certain intervals during the operation of the loom to engage the teeth of the ratchet and impart a partial rotation to the shaft 40 upon which is mounted the sprocket 43 that drives the pattern chain. It will thus be seen that the pattern chain 44 is moved intermittently by the pawl when the border and severing cords are woven into the cloth.

Means are provided to prevent the shaft 40 from overrunning under the pull exerted by the pawl 77, and as shown in Figs. 2 and 3 said means comprises a wheel 83 fixed to said shaft and a flat spring 84 secured to the loom frame. The wheel 83 is provided with flat surfaces *m* on its periphery corresponding in number to the number of teeth in the ratchet 81 and sprockets 43 and 45, said surfaces being adapted to be engaged one at a time by the free end of the spring 84 as the shaft is given its step by step rotation. In this manner the ratchet is advanced to the extent of only one tooth by each movement of the pawl,

the spring 84 preventing its further movement by the pressure exerted on its corresponding surface *m* on the wheel 83.

When plain weave is being made in the cloth, as in the body and hems of the handkerchief, the pawl 77 is disengaged from the ratchet 81 by means which will now be described. Referring to Figs. 1 to 6 inclusive, at 85 is shown a ratchet which is loosely mounted on a stud 86 adjustably secured by a nut 87 to a bracket 88 which is rigidly fixed to the side frame F of the loom. This ratchet is intermittently rotated by a pawl 10 (see Figs. 1 and 5) which is pivotally mounted on a stud 124 adjustably secured by nuts 89 to a bracket 90 fixed to the lower end of one of the lay swords 26. The pawl is held in engagement with the ratchet by a flat spring 91. Loosely mounted on the stud 86 is a gear 92 which is interlocked with the ratchet for rotation therewith as shown at 93 in Fig. 4. The gear 92 meshes with a gear 94 loosely mounted on a stud 95 rigidly secured to a bracket 96 fixed to the side frame F. Loosely mounted on the stud 95 is a sprocket 11 which is interlocked with the gear 94 for rotation therewith as shown at 97 in Fig. 4. This sprocket engages the forward end of a chain 98, herein termed the "multiplier chain," which extends rearwardly in a plane parallel to the loom frame and at its rear end runs over a sprocket 99 loosely mounted on the outer end of the shaft 40, which drives the pattern chain. It comprises a series of links 25 for engagement with the sprockets 11 and 99 and is provided on its periphery with cams arranged at predetermined intervals and adapted to engage a roller 12 on the outer end of a lever 13. The lever 13 (see Figs. 2, 3 and 6) is provided on its inner end with a roller 100 which engages the under side of the pawl 77, and forms supporting means for said pawl during its movement by the eccentric 76. The lever 13 is loosely mounted intermediate its ends on a stud 101 projecting from the frame of the loom and is held in place thereon by nuts 14 which are threaded onto the reduced end portion of said stud. The outer roller 12 is normally held in contact with the periphery of the multiplier chain by a coiled spring 102 (see Fig. 2) which is secured at one end to the outer arm of the lever and at the other end to the loom frame. It will thus be seen that when the roller 12 on the outer arm of the lever 13 is riding on the periphery of the plain links of the multiplier chain, the inner arm will be raised to disengage the pawl 77 from the teeth of the ratchet 81 as shown in Fig. 6. When the outer arm of the lever 13 is raised by the cams on the multiplier chain the inner arm of the lever is depressed, permitting the pawl 77 to engage the ratchet 81 and impart motion to the shaft 40.

The multiplier chain 98 through its cams

keeps the pattern chain 44 in motion until the pattern is completed and for the particular pattern illustrated in Fig. 7 comprises forty-three links consisting of thirty-two plain links indicated at 15, two links with cams 16 attached thereto, three plain links indicated at 17, one link with a cam 18 attached thereto, three more plain links indicated at 19, and two links with cams 103 attached thereto to complete the chain. The cams 16, 18 and 103 actuate the lever 13 to permit the pawl 77 to engage the ratchet 81 and impart motion to the pattern chain. As shown in Figs. 1 and 3 the cams 16 are engaging the roller 12 on the outer end of the lever 13, thus raising that end of the lever. At this time the inner end of the lever is depressed, permitting the pawl 77 to engage the ratchet 81 and drive the shaft 40. This shaft is driving the pattern chain which as heretofore stated is actuating the treadle engaging mechanism to restrain the harnesses while the first cord 36 of the border *b* is being laid. The cams 16 are adapted to actuate the lever 13 to permit continuous operation of the pattern chain until the first group of eight cams 70 thereon have actuated the treadle engaging mechanism to restrain the harnesses until the border *b* is completed. At the completion of the border *b* the cams 16 will have passed from under the roller 12 and the lever 13 will be actuated by the spring 102 to disengage the pawl 77 from the ratchet 81 thus stopping the pattern chain. On the continued movement of the multiplier chain in the direction of the arrow shown in Fig. 3, the loom will be weaving plain cloth constituting the hem *d* of the handkerchief. This operation takes place during the travel of the three plain links 17 under the roller 12 of the lever. When the cam 18 engages the roller 12, the lever 13 is again actuated to permit the pawl 77 to engage the ratchet and drive the pattern chain, at which time the severing cord is laid. The travel of the next three links 19 in the multiplier chain permit the weaving of plain cloth which constitutes the hem *u* of the succeeding handkerchief and the cams 103 permit the pawl 77 to again engage the ratchet and drive the pattern chain while the adjacent border (not shown) is put in. The travel of the plain links designated 15 then give the time necessary for the loom to make the body of the handkerchief which is of plain weave, before the cams again actuate the lever 13 to permit the continuation of the pattern.

As previously stated, the take-up motion, generally indicated at T in Fig. 1, draws down the cloth after it is woven and winds it upon the drum R. This action must take place after the reed *r* beats up each pick of the filling in the plain weave which constitutes the body and hems of the handkerchief,

but must be stopped temporarily while the cords of the borders and the severing cords are being laid to make the picks thereof more compact in the finished cloth. Means are provided for checking the take-up motion during this operation, and as shown in Fig. 1, said means comprises a flexible connection indicated at 105, which is secured at one end to the arm 106 of the locking pawl lever 33 and extends downwardly over the shaft 22 of the spool W, thence over a pulley 107 and forwardly to its connection at 108 with the lower end of the arm 60 previously referred to for actuating the treadle engaging mechanism. It will thus be seen that when the treadle engaging mechanism is actuated to restrain the harnesses while the cords of the borders and the severing cords are being laid, the take-up motion will be checked, thus permitting the completed cord to be laid before the cloth is again taken up. When the plain weave of the body and hems of the handkerchief is made, the take-up motion will be permitted to operate as is ordinarily the case after each pick of the filling is laid.

The operation of the herein described loom will be apparent from the foregoing description but may be briefly reviewed as follows:

With the loom in operation and the first cord 36 of the border *b* being laid, the parts will be in the position shown in Figs. 1, 2 and 3, wherein the cams 16 of the multiplier chain 98 are actuating the lever 13 to permit the pawl 77 to engage the ratchet 81 and drive the pattern chain 44. The first cam 70 on the pattern chain 44 is actuating the treadle latch mechanism to engage the treadle and restrain the harnesses. This action holds the warp threads in the formation of the shed S as shown in Fig. 1 for the passage of the shuttle in laying the threads of the cord 36. During this operation the takeup motion T has been stopped by the action of the arm 60 and intermediate connection 105 in disconnecting the locking pawl 32 from the ratchet 28. This permits the cord 36 to be completed before the cloth is again taken up which results in more firmly compacting the threads of said cord in the finished cloth. At the completion of the first cord 36 the pattern chain 44 releases the treadle engaging mechanism to permit the laying of the first single thread 37 of the border *b* at which time the takeup motion T is permitted to draw down the cloth and wind it upon the drum R. In this manner the entire border *b* is woven, the pattern chain being advanced during this operation in the direction of the arrow shown in Fig. 3 by the action of the pawl 77 which engages the ratchet 81 while the lever 13 is engaged by the cams 16 on the multiplier chain. After the completion of this border the cams 16 on the multiplier chain release the lever 13 from upright pressure on the pawl 77 and permits the spring

102 to disengage the pawl 77 from the ratchet 81 (see Fig. 2). At the same time the treadle latching mechanism is released, thus freeing the treadle and permitting the harnesses to operate under the action of the cam *c* and the spring 35 to weave the plain cloth constituting one of the hems *d* of the handkerchief. During this operation the takeup motion is permitted to operate in the usual manner. The multiplier chain advances in the direction of the arrow shown in Fig. 3 during this operation and at the completion of the hem the cam 18 on said chain engages and actuates the lever 13 to permit the pawl 77 to engage the ratchet 81 and again put the pattern chain in motion. During this movement of the pattern chain, the cam 71 thereon actuates the treadle latching mechanism to engage the treadle to restrain the harnesses while the severing cord *e* is being laid, during which operation the takeup motion is again checked. Thereafter the pawl 77 is disengaged from the ratchet 81 by the action of lever 13 when the cam 18 passes out from engagement with the roller 12 during further advance of the multiplier chain at which time the hem indicated at *u* in Fig. 7 is woven, during which operation the takeup motion is permitted to operate. At the completion of this hem the cams 103 on the multiplier chain 98 actuate the lever 13 to permit the pawl 77 to again put the pattern chain in motion. During this movement of the pattern chain the cams 72 thereon actuate the treadle engaging mechanism to restrain the harnesses while the adjacent border is being woven. After the cams 103 pass from engagement with the lever 13 at the completion of this border the harnesses are free to be operated by the cam *c* and spring 35 to weave the plain cloth constituting the body of the handkerchief, such a portion being indicated at *a* in Fig. 7. It will be understood that the reed *r* is beating up each pick of the plain weave after it is laid and also that the takeup is operating in the usual manner to wind the finished cloth on the drum R.

Referring now to Fig. 8 of the drawings there is shown in diagram a fragmentary view of dimity cloth made in a loom having pattern controlling mechanism embodying the invention attached thereto. This cloth is known as "narrow check weave" and comprises a series of cords coming off the warp spaced at equidistant short intervals with plain weave therebetween and a filling composed of a series of cords similarly spaced with plain weave therebetween. As herein shown 120 designates the warp cords of three threads each and 121 the cords made of the weft threads or filling having three picks each. Between each of the cords 121 is plain weave indicated at 122 having three picks of filling. The cords 121 intersect the cords 120 to form narrow checks indicated at 123.

When narrow check weave such as dimity is made on the loom shown in Fig. 1, the pawl 10 is disengaged from the ratchet 85 and is turned down into the position shown in dotted lines in this figure where it is rigidly secured in place by the nuts 89 on the stud 124, thus eliminating the operation of the multiplier chain 98. The lever 13 is turned up into the position shown in dotted lines in Fig. 2 and securely bolted in that position by the nuts 14 on the stud 101, thus permitting the pawl 77 to engage the ratchet 81 at all times during this operation. The pattern chain 44 is then removed and a pattern chain 130 having a series of cams on its periphery arranged as in Fig. 9 is applied to the sprockets 43 and 45. As herein shown this chain is provided with a cam 131 on every third link, there being two plain links indicated at 132 between each pair of cams. It will thus be seen that a pattern of this type is laid by the action of the cams of the pattern chain 130 on the treadle engaging mechanism, said pattern chain being in continuous step by step rotation under the action of the pawl 77. The take-up motion T is checked while the cords 121 are being laid as in weaving handkerchief cloth.

Referring now to Fig. 10, there is shown in diagram a fragmentary view of "broken-stripe" cloth made in accordance with the present invention. The stripes indicated at 140 are off the warp and are overlaid or "broken" by a single pick of the filling at regular intervals. As herein shown every fourth pick 141 of the filling overlays the stripe while the three picks designated 142 between each pair of picks 141 runs underneath the stripe. The balance of the cloth is made up of plain weave.

When cloth of the above description is woven, the mechanism is arranged the same as for making dimity and a pattern chain similar to the one shown in Fig. 11 is employed. In this case the take-up motion is disconnected from the treadle engaging mechanism so that the cloth is drawn down as it is woven and wound upon the drum R by a continuous step by step movement.

When the loom is to be used for weaving plain cloth it is simply necessary to throw the harness engaging mechanism out of operation by securely fixing the lever 13 in a position to disengage the pawl 77 from the ratchet 81 as shown in Fig. 6, and stop the movement of the multiplier chain 98 by disengaging the pawl 10 from the ratchet 85. The connection 105 between the take-up motion and the treadle engaging mechanism is also released.

Due to the fact that the mechanism herein-described is applied to a plain loom in a manner to cooperate with the two harnesses thereon to control the pattern, the drawing-in operation which consists of drawing each individual end from the warp through the eyes of the harness heddle and reed may be performed by a machine known as a drawing-in machine. This operation is now done by hand on the looms equipped with pattern controlling mechanisms now in common use.

From the foregoing description it will be seen that a plain loom equipped with pattern controlling mechanism embodying the invention is adapted to weave plain cloth in a manner and as effectively as if it were without attachments. It is also adapted at very short notice to weave pattern cloth of comparatively wide check weave such as handkerchief cloth and the like, narrow check weave such as dimity and the like, and broken-stripe cloth such as dress goods, shirting, etc.

Furthermore the pattern controlling mechanism herein-described is comparatively simple and can be made and attached to a loom for about twenty per cent of the cost of similar mechanisms now in common use. Due to its simplicity it requires less attention which results in a saving of labor. As is well known in the textile industry, one fixer now takes care of not over one hundred and twenty looms for weaving plain cloth or sixty looms for weaving pattern cloth. As to power, it takes considerably less with this attachment applied to a plain loom, and as to speed the output can be as high as one hundred and eighty picks per minute against a maximum of one hundred and sixty picks with the looms now employed for weaving pattern cloth. As to weaving costs, at the present time one operator runs eight to ten plain looms at a weekly wage of eighteen dollars, or six to eight looms for weaving pattern cloth at a weekly wage of twenty-four dollars. With this attachment on a plain loom one operator could handle from eight to ten looms for weaving pattern cloth at a weekly wage of eighteen dollars.

It will thus be seen that the output per operator is greater and the cost in wages less than for previous methods of weaving pattern cloth. Furthermore, the mechanism herein-described may be attached to as many plain looms in a mill as is desirable without interfering with the weaving of plain cloth thereon, or without requiring extra floor space as is the case where pattern controlling mechanisms now employed are attached to special looms adapted for the sole purpose of weaving pattern cloth.

The foregoing advantages therefore result particularly in a lower first cost, less power consumed, lower labor costs, increased production and a saving in floor area.

We claim:

1. In combination with a loom for weaving plain cloth, an attachment for said loom comprising a pattern-controlling chain and a pair of sprockets therefor, shafts on which said sprockets are mounted, a series of cams

mounted on said chain arranged in predetermined number and spacing according to the pattern to be woven, a treadle connected with the harnesses, a rotary shaft, cams mounted on said shaft adapted to engage the treadle to actuate the harnesses, a ratchet mounted on one of the sprocket shafts of the pattern chain, a pawl which engages with said ratchet, and an eccentric mounted on the cam shaft having driving connection with said pawl to drive the pattern chain.

2. In combination with a loom adapted to weave plain cloth, an attachment for the loom comprising a rotary shaft, a cam carrier, means whereby said shaft drives said cam carrier, a series of cams mounted on said carrier and means actuated by said cams to restrain the harnesses for predetermined intervals of time while the weft threads continue to be laid and thereby control the number of threads in a cord in the pattern, said restraining means comprising an arm, a support to which one end of said arm is pivoted, a flexible member connected to the other end 25 of said arm, a guide around which said flexible member passes, a latch to which the other end of said flexible member is connected, said latch being provided with a hook adapted to engage the harness treadle to restrain the movement of the harnesses.

3. In combination with a loom adapted to weave plain cloth, an attachment for the loom comprising a rotary shaft, a cam carrier, a series of cams mounted on said carrier and means actuated by said cams to restrain the harnesses for predetermined intervals of time while the weft threads continue to be laid and thereby control the number of threads in a cord in the pattern, said restraining means comprising an arm, a support to which one end of said arm is pivoted, a belt, the other end of said arm being connected to one end of said belt, a guide around which said belt passes, a latch to which the other end of said belt is connected, a harness and treadle, said latch being adapted to engage the harness treadle to restrain the movement of the harnesses, and means which are operative to release the said latch from the harness treadle 50 when the cam on the pattern chain is disengaged from said arm.

4. In combination with a loom adapted to weave plain cloth, an attachment for the loom comprising a rotary shaft, a cam carrier, means whereby said shaft drives said carrier, a series of cams mounted on said carrier and means actuated by said cams to restrain the harnesses for predetermined intervals of time while the weft threads continue to be laid and thereby control the number of threads in a cord in the pattern, said restraining means comprising an arm, a support to which one end of said arm is pivoted, a belt, the other end of said arm being connected to one end of said belt, a guide around which

said belt passes, a latch to which the other end of said belt is connected, a harness and treadle, said latch being adapted to engage the harness treadle to restrain the movement of the harnesses, said pivoted arm having a member in position adapted to be engaged by the several cams on said cam carrier to rock said arm and actuate the intermediate connections whereby the rocking of said arm will cause the latch to make locking engagement with the treadle.

5. In combination with a loom adapted to weave plain cloth having harnesses, an attachment for the loom whereby it is adapted to weave checks or broken stripes, said attachment comprising a rotary shaft, a sprocket made fast thereto, a second sprocket, a pattern chain in operative engagement with both of said sprockets, a series of cams mounted on said chain and means actuated by said cams to restrain the harnesses for predetermined intervals of time while the weft threads continue to be laid and thereby control the number of threads in a cord in the pattern and means for intermittently actuating the pattern chain, said means comprising a ratchet mounted on the shaft which carries the fixed sprocket, a feed pawl engaging with said ratchet, a rotary cam shaft, shedding cams mounted thereon and an eccentric mounted on the said cam shaft.

6. In combination with a loom adapted to weave plain cloth, an attachment for the loom comprising a rotary shaft, a sprocket made fast thereto, a second sprocket, a pattern chain in operative engagement with both of said sprockets, a series of cams mounted on said chain and means actuated by said cams to restrain the harnesses for predetermined intervals of time while the weft threads continue to be laid and thereby control the number of threads in a cord in the pattern, means for intermittently actuating the pattern chain, said means comprising a ratchet mounted on the shaft which carries the fixed sprocket, a feed pawl engaging with said ratchet, a rotary cam shaft, shedding cams mounted thereon, an eccentric mounted on said cam shaft and means for preventing overrunning of the shaft which carries the fixed sprocket and ratchet, said means consisting of a wheel mounted fast on said shaft, said wheel having flat faces on its periphery and a spring brake which engages said flat faces.

7. In combination with a loom adapted to weave plain cloth having harnesses, a harness treadle and a cam shaft with a cam adapted to actuate the harness treadle, an attachment for the loom whereby it is adapted to weave checks or broken stripes, said attachment comprising a rotary shaft, a sprocket made fast thereto, a second sprocket, a pattern chain in operative engagement with both of said sprockets, a series of cams mount-

ed on said chain and means actuated by said cams to restrain the harnesses for predetermined intervals of time while the weft threads continue to be laid and thereby control the number of threads in a cord in the pattern, means for intermittently actuating the pattern chain, said means comprising said cam shaft, a ratchet mounted on the shaft which carries the fixed sprocket, a feed pawl engaging with said ratchet and an eccentric mounted on the said cam shaft, means for disengaging the feed pawl from said ratchet, said means comprising lay swords, a ratchet loosely mounted on a stud and a pawl pivotally mounted on a member projecting from one of the said lay swords, a sprocket, a multiplier chain which at one end engages with said sprocket and has driving connection with said last named ratchet, a series of cams carried by said multiplier chain at predetermined intervals which are adapted to engage one end of a lever, said lever being pivoted intermediate its ends, the other end of said lever engaging the pawl which actuates the pattern chain feed, said lever normally holding the feed pawl out of engagement with the feed ratchet and cams on said multiplier chain which are adapted to tip said lever and permit the pawl which actuates the pattern chain to engage the driving ratchet of the pattern chain.

8. In combination with a loom adapted to weave plain cloth, an attachment for the loom whereby it is adapted to weave checks or broken stripes, said attachment comprising a rotary shaft, a sprocket made fast thereto, a second sprocket, a pattern chain in operative engagement with both of said sprockets, a series of cams mounted on said chain and means actuated by said cams to restrain the harnesses for predetermined intervals of time while the weft threads continue to be laid and thereby control the number of threads in a cord in the pattern, means for intermittently actuating the pattern chain, said means comprising a shaft, a cam carried by said shaft adapted to actuate the harness treadle, a ratchet mounted on the shaft which carries the fixed sprocket of the pattern chain, a feed pawl engaging with said ratchet and an eccentric mounted on the said cam shaft, means for disengaging the pattern chain feed pawl from its ratchet, said means comprising lay swords, a ratchet loosely mounted on a stud and a pawl pivotally mounted on a member projecting from one of the lay swords, a sprocket mounted on a stud carried by the frame, said last named ratchet having driving connection with said sprocket, a multiplier chain engaging said sprocket and a sprocket mounted on the shaft that drives the pattern chain, a lever pivoted intermediate its ends, a series of cams carried by said multiplier chain at predetermined intervals which are adapted to engage one

arm of said lever, the other arm of said lever engaging the pawl which actuates the pattern chain feed, whereby when one of the cams on the multiplier chain engages the said lever it will tip the lever thereby permitting the pawl to engage with the feed ratchet and feed the pattern chain and means whereby when the said cam is disengaged from the said lever, said lever will be tipped in the reverse direction and disengage the driving pawl from the pattern chain driving ratchet.

9. In a two harness loom having a cloth take-up motion including a ratchet and pawl feed, a treadle to operate the harnesses, a take-up feed, a feed ratchet, a pivoted arm and means connected therewith for locking the treadle at predetermined times and means for suspending the cloth take-up motion while the treadle is locked during the laying of a plurality of picks, said means comprising a lever, a locking pawl carried thereby adapted to engage with said feed ratchet to restrain the movement of the take-up feed, and a flexible member connected at one end with one arm of said locking pawl lever, said flexible member being connected at its other end with said pivoted arm of the harness restraining mechanism.

10. In combination with a loom adapted to weave plain cloth, an attachment for the loom comprising a rotary shaft, a cam carrier, means whereby said shaft drives said cam carrier, a series of cams mounted on said carrier and means actuated by said cams to restrain the harnesses for predetermined intervals of time while the weft threads continue to be laid and thereby control the number of threads in a cord in the pattern, an arm pivoted at one end to a support, a flexible member connected to the other end of said arm and means connected with said flexible member adapted to restrain the movement of the harnesses.

11. In combination with a loom adapted to weave plain cloth, a carrier on which are mounted a plurality of cams, means actuated by said cams for restraining the movement of the harnesses for predetermined intervals while the weft threads continue to be laid and thereby control the number of threads in a cord in the pattern, said restraining means comprising an arm pivoted to a support, a flexible member connected at one end to said arm, the other end of said flexible member being connected to a latch adapted to restrain the treadle and means which are rendered operative to release the latch from the treadle when the cam carrier is disengaged from said arm.

12. In combination with a loom adapted to weave plain cloth, a carrier on which are mounted a plurality of cams, means actuated by said cams for restraining the movement of the harnesses for predetermined intervals while the weft threads continue to be laid

and thereby control the number of threads in a cord in the pattern said restraining means comprising an arm pivoted to a support, a flexible member connected at one end to said arm, the other end of said flexible member being connected to a latch adapted to restrain the treadle, means which are rendered operative to release the latch from the treadle when the cam carrier is disengaged from said arm, and means carried by said pivoted arm adapted to be actuated by said cams to cause the latch to make locking engagement with the treadle.

In testimony whereof we affix our signatures.

JOSEPH THEXTON, JR.
HENRY TOMLINSON.
